(57) **CLAIM**

The ornamental design for a mounting structure for detection apparatus, as shown and described.

DESCRIPTION

FIG. 1 is a front, right and top perspective view of a mounting structure for detection apparatus showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a left, front and top perspective view thereof;

FIG. 9 is a left, rear and bottom perspective view thereof;

FIG. 10 is a right, front and top perspective view of a mounting structure for detection apparatus with unclaimed environment; and,

FIG. 11 is a left, front and top perspective view of a mounting structure for detection apparatus with unclaimed environment.

The broken lines in the drawings depict portions of the mounting structure for detection apparatus that forms no part of the claimed design. The additional broken lines in FIGS. 10-11 depict environmental subject matter that forms no part of the claimed design.
